UNITED STATES PATENT OFFICE.

LEON E. BUTLER, OF CHICAGO, ILLINOIS.

MOLDING DEVICE.

1,351,157.

Specification of Letters Patent. Patented Aug. 31, 1920.

Application filed April 12, 1919. Serial No. 289,527.

To all whom it may concern:

Be it known that I, LEON E. BUTLER, a citizen of the United States, residing in the city of Chicago, county of Cook, and State 5 of Illinois, have invented a certain new and useful Improvement in Molding Devices, of which the following is a specification.

My invention is designed to provide a molding device for the construction of an 10 article of fusible or friable material and is designed to be used by children, and has for its object to provide means to construct a mold in which a child may form various figures.

15 My means of accomplishing the foregoing object may be more readily understood by having reference to the accompanying drawings which are hereunto annexed and are a part of this specification in which—

20 Figure 1 is a top or plan view of my improved device.

Fig. 2 is a side elevation.

Fig. 3 is a cross section taken on the line double 3 in Fig. 2.

25 As shown in the drawings my device comprises a base 10, which is preferably provided with legs 11 and 12. This base has mounted in its center a pattern plate 13, which has a figure 14 formed in relief on

30 each side of the plate 13, the two figures being such that when united they will form a complete whole. The pattern plate 13, is secured to the base 10 by means of an inverted U shaped rod 15, the ends 16 and 17 of which

35 project downwardly through the base 10 and are secured by means of nuts 18 and 19 though any other suitable or convenient means of fastening may be employed. It will be apparent from the foregoing descrip-

40 tion that by tightening the ends 18 and 19 the U shaped member 15 can be drawn down tightly against the pattern plate 13 and thus hold it firmly in position.

On each side of the base 10, I mount two 45 channels 20 and 21 which are hinged upon pins or pivots 22 and 23 mounted in outwardly extending portions 24 and 25 of the base 10. These channels are adapted to be swung so as to engage the side of the pattern 50 plate 13 when in position and to be swung away therefrom, as clearly shown in the dotted line in Fig. 3 when desired.

Means to hold the edges 26 and 27 tightly against the face of the pattern plate 13 are 55 provided by clamps 28 and 29 which pass

through orifices formed in the pattern plate, the ends 30 and 31 of which are bent as clearly shown in Fig. 1 to conform to the outer surface of the channels 20 and 21.

The operation of the device is as follows: 60

The channels 20 and 21 are swung inwardly until the edges 26 and 27 thereof engage the face of the pattern plate 13. The clamps 28 and 29 are then swung into the position shown in Fig. 1, the ends 30 and 31 65 serving to hold the channels 20 and 21 tightly against the face of the pattern plate. The material 33, of which the mold is to be formed is then poured into the channel and allowed to harden, when by swinging the 70 clamps 28 and 29 into the position shown in the dotted lines in Fig. 2, the channels 20 and 21 can be swung outwardly to the position shown in the dotted lines in Fig. 3, when the mold can be withdrawn from be- 75 tween the channels and when the two are placed together there will be a depression corresponding to the shape of the figure which is formed in relief upon the face of the pattern plate 13. The wax or other 80 friable material can then be poured into this space and a figure will be molded corresponding to the figure 14 shown in relief of the face of the pattern plate.

It will be apparent to persons skilled in 85 the art that any desired figure may be employed upon the face of the pattern plate.

Having described my invention what I regard as new and desire to secure by Letters Patent of the United States is: 90

1. The combination with a base of a pattern plate having a relief on each side, means to hold said plate rigidly in position, a pair of channels pivoted to said base, adapted to engage said plate with their 95 edges when in position and to be swung away therefrom and means to hold said channels tightly against said plate.

2. The combination with a pattern plate having a relief on each side, a base, means 100 hinged to the base adapted to receive and hold plastic material, whereby a mold of two halves of a figure is made, a clamp to hold said means tightly against said plate while the plastic material is being poured 105 and hardened.

3. The combination with a base of a pattern plate having a relief on each side, each of which forms one half of a figure and is adapted to register with the other, means to 110

hold said plate rigidly in position, a pair of channels pivoted to said base adapted to engage said plate with their edges and to be swung away therefrom and means to hold 5 said channels tightly against said plate.

4. The combination with a base of a pattern plate having a relief on each side, each of which forms one half of a figure and is adapted to register with the other, a U 10 shaped member the ends of which pass through said base, nuts mounted on the ends

thereof to hold said plate rigidly in position, a plurality of legs upon which said base is mounted, a pair of channels pivoted to said base adapted to engage the face of 15 the pattern plate with their edges and to be swung away therefrom, a clamp mounted in said pattern plate the ends of which hold said channels tightly against the pattern plate.

LEON E. BUTLER.
